C. E. FRAZIER

PACKER

Filed Nov. 24, 1923

Fig. 2.

Charles E. Frazier, Inventor

Fig. 1.

By Jesse R. Stone

Attorney

UNITED STATES PATENT OFFICE.

CHARLES E. FRAZIER, OF DALLAS, TEXAS, ASSIGNOR TO THE GIBERSON CORPORATION, OF DALLAS, TEXAS.

PACKER.

Application filed November 24, 1923. Serial No. 676,782.

To all whom it may concern:

Be it known that I, CHARLES E. FRAZIER, a citizen of the United States, residing at Dallas, Dallas County, Texas, have invented 5 a certain new and useful Improvement in Packers, of which the following is a specification.

My invention relates to an improvement in packers for use in deep wells. It pertains 10 more particularly to so-called flow packers.

It has for its object the provision of a packer which will serve to prevent the passage of fluid under pressure upwardly around the pump tubing inside the casing.

15 Referring to the drawing herewith, Fig. 1 shows a central longitudinal section through a well casing having a pump tubing therein partly in elevation with the invention thereon. Fig. 2 is a transverse section on 20 the plane 2—2 of Fig. 1. Like numerals of reference designate like parts in both the views.

In well drilling, it is sometimes found that, when the producing sand is reached, 25 insufficient gas pressure is obtained to cause the fluid in the hole to flow from the top thereof. It is therefore of advantage to place a pipe of smaller diameter inside the casing and to close the space between the 30 tubing and casing, by means of a packer so as to confine the pressure to the interior of the tubing.

I have provided a packer which is particularly adapted to this purpose. In Fig. 35 1, the casing is designated at 3. Inside the said casing is a tubing 4 upon which is mounted the flow packer constituting our invention. A special short length 2 of pipe is reduced in diameter at its upper end 5 40 to provide a seat for a cup 6 of rubber or other flexible composition. The shoulder 7 formed at the lower end of the reduced portion 5 furnishes a seat for a ring 8 adapted to extend beyond said shoulder and form 45 a support for the base portion of the cup 6.

The cup is held downwardly upon the ring 8 by means of a thimble 9 which is formed in the shape of an inverted cup, the upper end of which fits closely about the 50 portion 5 of the tubing. The coupling 10 which secures the pipe 2 to the tubing may serve as a clamp to force the thimble downwardly against the cup 6 and hold it clamped firmly in position.

55 The outer surface and lower edge of the

cup 6 are protected by means of a series of spaced wires or rods 11. To receive these rods the outer face of the cup is grooved as shown at 12 in Fig. 2, thus allowing the outer surface of the rods to come flush 60 with the outer surface of the cup. The upper ends of said rods are bent inwardly and fit within recesses 13 formed in the cup to receive them.

The said rods or wires 11 are bent to 65 the shape of the cup and are inclined inwardly below the edge of said cup to a point spaced somewhat from the pipe 2 and then are extended directly downward and the lower ends are fitted within opening 14 in a ring 15 secured to the pipe 2. Below the ring, the rods are bent outwardly to limit the movement of the rods relative to the ring.

70 It will be noted that the lower end of 75 the cup is formed with a cylindrical outer surface 16 adapted to contact with the inner face of the casing. This will serve to form a closure between the tubing and the casing which, under pressure of the fluid 80 below the cup will be sufficient to prevent the passage upwardly of fluid outside of the tubing.

In the use of this device, the packer will be secured upon the tubing at the desired 85 point and when thus mounted and assembled, as shown in the drawing, the tubing will be gradually lowered into the well until the desired point is reached. The pressure of gas and liquid below the packer 90 will tend to expand the cup outwardly and by thus closing passage for the fluid outside the tubing, all escape of gas or oil will take place through the tubing alone. The flexible cup 6 will be supported partly by 95 the thimble 9 and partly by the rods 11 and the interior of the casing. If it is found that the well will not flow, the pump may be inserted into the tubing and the presence of the packer will assist in the operation 100 of the pump by directing all fluid upwardly into the pump barrel.

If it is desired to withdraw the tubing from the well, the tubing may be raised in the usual manner and the flexible cup 105 6 will automatically contract as it is drawn upwardly, thus allowing free passage through any fluid which may accumulate above the packer.

The wires or rods 11 serve not only to 110

support the cup, but protect it from wear or mutilation while it is being introduced into the hole or withdrawn therefrom.

It will be obvious that this type of packer is simple and cheap in construction and not subject to mutilation or damage in use as is the ordinary packer. Further objects and advantages will be apparent to one skilled in the art without further description.

10 While I have described the packer as adapted for pumping purposes it is obvious that the device will be capable of a wide application, and I do not wish to be confined to any particular use to which it is put.

15 Having thus described my invention, what I claim as new and desire to protect by Letters Patent is:

1. A packer for well operations comprising a cylindrical supporting member, a shoulder thereon, a ring on said shoulder, a flexible downwardly-flaring cup supported on said ring, a reinforcing thimble of rigid material above said cup, and rods embedded in the outer surface of said cup, 25 extending below said cup and having engagement in a ring on said supporting member.

2. A packer for well operations comprising a supporting member, a radial shoulder thereon, a downwardly flaring cup of flexible material on said shoulder, a reinforcing thimble over the upper end of said cup, means to clamp said thimble against said cup and means to protect the outer face of 35 said cup.

3. A packer for well operations comprising a supporting member, a downwardly flaring cup of flexible material on said support, a thimble on the upper end of said cup, means on said support to clamp said

cup and thimble firmly thereon, and resilient protecting means on the outer face of said cup.

4. A packer for well operations comprising a supporting member, a downwardly flaring cup of flexible material thereon, a rigid thimble over the upper end of said cup, means to clamp said cup and thimble on said support and a series of protecting rods engaging between said cup and thimble and projecting downwardly below said cup.

5. A well packer comprising a supporting member, a downwardly flaring cup of flexible material thereon, means to clamp said cup in position on said member, and a series of resilient members secured adjacent the base of said cup, acting to protect and support the outer face of said cup and extending beyond the lower edge of said cup for the purpose stated.

6. A well packer for use in a well casing comprising a supporting tubular member, a flexible, downwardly-flaring cup secured thereon, a reinforcing thimble above said cup, a series of rods secured between said cup and thimble and extending along said tubular support to which said rods are slidably attached.

7. A well packer for use in a well casing, comprising a supporting tubing, a downwardly flaring cup on said tubing adapted to contact with said casing, means to clamp said cup on said tubing, and rods extending along the outer face of said cup to support and protect the same.

In testimony whereof I hereunto affix my signature this 19th day of November, A. D. 1923.

CHARLES E. FRAZIER.
